TUMBLER OR SIMILAR ARTICLE

James Lloyd Thrush, Lancaster, Ohio, assignor to Anchor Hocking Corporation, Lancaster, Ohio

Filed Apr. 21, 1971, Ser. No. 136,300

Term of patent 14 years

Int. Cl. D7—01

U.S. Cl. D36—8

FIG. 1 is an elevational view of a tumbler or similar article showing my new design in the size and proportions of a water glass;

FIG. 2 is a top view thereof;

FIG. 3 is a bottom view thereof;

FIG. 4 is an elevational view of a tumbler or similar article showing my new design in the size and proportions of a cocktail glass; and

FIG. 5 is an elevational view of a tumbler or similar article showing my new design in the size and proportions of a juice glass.

I claim:

The ornamental design for a tumbler or similar article, substantially as shown and described.
